UNITED STATES PATENT OFFICE.

SIGMOND F. BECK, OF NEW HAVEN, CONNECTICUT.

COACH-DOOR LATCH.

Application filed February 8, 1924. Serial No. 691,383.

This invention relates to latch operating mechanisms, and although it is of general application it is especially adapted for use in doors where there is very little clearance available for the latch spindle as is commonly the case in coach or closed automobile body doors where the glass as it moves from its closed position to the open position passes by the spindle of the outside operating handle.

It is, therefore, an object of the invention to provide a latch operating mechanism which will retract the latch when operated in either direction, but which may be located closely adjacent the edge of the door.

It is also an object of the invention to provide a device of this character which will give the result specified but which will be very simple in construction requiring but few parts and will, therefore, be comparatively cheap to manufacture and cannot be easily gotten out of order in operation.

With the foregoing and other objects in view I have devised the construction illustrated in the accompanying drawing, in which—

Fig. 1 is a front view of a portion of a door showing my improved latch operating mechanism applied thereto.

Fig. 2 is a partial elevation and a partial section of the edge of said portion of the door looking from the right of Fig. 1.

Fig. 3 is a sectional plan view through the latch looking upwardly from the bottom of Fig. 1.

Fig. 4 is a longitudinal section through the latch casing substantially on line 4—4 of Fig. 3, but showing the latch operating mechanism in elevation.

Fig. 5 is a plan view of one of the follower elements.

Fig. 6 is a similar view of the other follower element, the elements in these two views being arranged in the relative positions they normally occupy when assembled in the latch.

Fig. 7 is an edge view of the follower shown in Fig. 6.

Fig. 8 is an end view of the operating bushing, and

Fig. 9 is a side elevation thereof.

In the usual latch operating follower arranged to retract the latch on turning of the latch spindle or knob in either direction, the follower is usually made in one piece, and for this reason clearance must be provided

to allow the idle wing to swing backwardly or toward the edge of the door when the spindle is rotated. This construction requires that the spindle be located a sufficient distance from the edge of the door to allow for this backward swing of these wings. This clearance could not be provided in the usual coach or closed automobile doors as there is not room enough between the edge of the window glass and the edge of the door, and therefore, the general practice is to use one way spindles, that is the latch can be retracted only by rotating the spindle in one direction. This, at times, is very annoying as it is natural for different people to turn the spindle in different directions in operating the latch bolt, and also a person naturally tends to rotate the spindle in opposite directions with the different hands, and even at different times with the same hand, so that a one way spindle often causes delay and more or less trouble.

To overcome these difficulties the inventor has devised a latch operating mechanism which will allow rotation of the spindle in either direction to retract the latch bolt, and which requires no more space than the one way spindle, so that it is adapted for use on coach or closed automobile doors.

In the drawing I have shown the latch operating mechanism as applied to a given type of latch but this is merely for the purpose of illustration as the type of latch is not important and my improved latch operating mechanism may be applied to numerous different types of latches as will be obvious. In the construction shown, however, I have shown a casing 10 mounted in a recess in the inner side of a coach door 11 and at the edge thereof as is common practice. Guided to slide within this casing is the latch bolt 12 forming a movable securing element projecting from the edge of the door, as shown and curved on the inner side 13 to react with the keeper, not shown, to retract the bolt in the usual manner when the door is closed. Extending through the door is the usual latch operating spindle 14 preferably substantially square in cross section and connected on opposite sides of the door with the usual operating handles 15 and 16 carried by the bolt 12 or suitable mechanism connected therewith. On opposite sides of the spindle the bolt is provided with shoulders 17 and 18. Mounted on the spindle, so as to rotate therewith, is a bush-

ing 19 provided with a projecting lug 20 on the outer wall thereof.

The followers for operating the latch bolt from the spindle comprise two elements 21 and 22, preferably flat plates, as shown in Figs. 5, 6 and 7, and have extending through them openings 23 and 24 for the passage of bushing 19 so that these followers are mounted on the bushing. These followers are each provided with a wing projection 25 and 26 respectively so located that when they are assembled on the bushing, as shown in Figs. 1 and 4, they project from the spindle in opposite directions and engage the shoulders 17 and 18 respectively of the bolt. Each follower 21 and 22 is cut away at one side of the openings 23 and 24, as shown at 27 and 28 in Figs. 5 and 6, and the cutaway portion is preferably in the form of a sector extending somewhat more than 90°, although this may vary depending upon the amount of movement required by the lug 20 in retracting the latch bolt. These cutaway portions provide shoulders 29 and 30 so arranged that when they are assembled on the bushing 19 they engage the opposite sides of the lug 20, as shown in Fig. 4, and the cutaway portions 27 and 28 extend in opposite directions from these shoulders and this lug.

The operation is as follows:

Referring to Fig. 4 it will be seen that rotation of the spindle 14 to the right or clockwise as viewed in this figure will move the lug 20 in the same direction, and as the shoulder 30 bears against the upper side of this lug, the follower 22 will rotate with the bushing, the projection 26 will move rearwardly or to the left, as shown in this figure, and by reaction on the shoulder 18 will retract the latch bolt against the action of the spring 31. During this movement in a clockwise direction the lug 20 will move around the cutaway portion 27 in follower 21 and this follower together with its projection 25 will remain stationary, and, therefore, no clearance is required for movement of this element to the right of its normal position as shown in Fig. 4. Likewise it will be apparent that upon rotation of the spindle to the left or counter-clockwise, as viewed in Fig. 4, the lug 20 will move in the same direction, and as it bears on its lower side against shoulder 29 carried by follower 21 this follower will be rotated with the bushing moving its projection 25 to the left, and by reaction on the upper shoulder 17 of the bolt will retract this bolt in the same manner. During this movement the lug 20 will move around the cutout portion 28 in follower 22 and this follower will remain stationary.

It will, therefore, be apparent that rotation of the spindle in either direction will rotate one only of the followers 21 and 22,

the other remaining stationary, and that, therefore, the bolt may be retracted by rotation of the spindle in either direction. However, as during rotation of the spindle in either direction the projection 25 or 26 as the case may be moves rearwardly away from the edge of the door and the other projection remains stationary and does not move toward the edge of the door no clearance is required to take care of this movement as would be the case if the two projections 25 and 26 were in one piece or on a single follower, as is now the general practice. It will, therefore, be apparent that the spindle 14 may be located closely adjacent the edge of the door allowing plenty of room for passage of the edge of the glass 32 as it is lowered to a position within the door, and therefore, this spindle, although it will retract the bolt when rotated in either direction, still may be placed as near the edge of the door as may the spindle which operates the bolt when it is rotated in one direction only, and thus will not interfere with the operation of the window.

It will also be apparent that the device is very simple in construction involving merely the two simple pieces to form the two followers, and so may be manufactured at low cost and will not be liable to be easily gotten out of order.

Having thus set forth the nature of my invention, what I claim is:

1. In a latch, a sliding bolt, a rotatable spindle, a bushing secured to said spindle, a lug carried by said bushing, a pair of relatively movable followers provided with wing projections extending in opposite directions and adapted to engage said bolt to retract the same, and shoulders carried by each of said followers in the path of movement of said lug and facing in opposite directions.

2. In a latch, a sliding bolt, a rotatable spindle, a bushing secured to said spindle, a lug carried by said bushing, a pair of relatively movable followers embracing said bushing and provided with wing projections extending in opposite directions and adapted to engage said bolt to retract the same, said followers being cut away to form shoulders to engage the opposite sides of said lug and to also form spaces for the free movement of the lug away from said shoulders.

3. In a latch, a sliding bolt provided with shoulders, a rotatable spindle, a bushing secured to the spindle, a pair of independent followers mounted on the bushing and adapted for movement relative thereto, said followers being each provided with a wing projection and arranged with the said projections extending in opposite directions from the spindle and adapted to engage respectively the shoulders on the bolt, and a lug carried by the bushing, said followers

being provided with shoulders arranged to respectively engage the opposite sides of the lug upon rotation of the spindle in opposite directions.

5. 4. In a latch, a sliding bolt provided with shoulders, a rotatable spindle, a pair of followers having wing projections extending in opposite directions from the spindle and adapted to engage said shoulders to retract 10 the bolt, said followers being each provided with an opening therethrough, a bushing on said spindle and mounted for relative rotation in said openings, said followers being cut away adjacent said openings to provide 15 shoulders facing in opposite directions and spaces leading from said shoulders, and a lug carried by said bushing and located in said cutaway portions and adapted to alternately engage the shoulders carried by the 20 respective followers upon rotation of the spindle in opposite directions.

5. In a latch a movable securing element, a follower connected with said securing element to retract the same, a rotatable spindle,

a bushing secured to said spindle, a lug carried by said bushing, and a shoulder carried by the follower in the path of movement of said lug in one direction whereby the follower will be operated to retract the securing element upon rotation of the spindle in a 25 corresponding direction, said lug adapted for movement independent of the follower upon rotation of the spindle in the opposite direction.

6. In a latch a movable securing element, 30 a rotatable spindle, a bushing secured to said spindle, a lug carried by said bushing, and a follower provided with an opening adapted to receive said bushing and having a wing projection adapted to retract the securing 35 element when moved in one direction, said follower being cut away to form a shoulder adapted to be engaged by said lug when the spindle is rotated in a corresponding direction and a space for free movement of said 40 lug in the opposite direction.

In testimony whereof I affix my signature.
SIGMOND F. BECK.
